HIS ATTORNEY

UNITED STATES PATENT OFFICE.

LEWIS C. MYERS, OF NEW YORK, N. Y., ASSIGNOR TO THE CENTURY MACHINE COMPANY, OF SAME PLACE.

DESIGN FOR A FRAME FOR SPRING-SCALES.

SPECIFICATION forming part of Design No. 30,050, dated January 24, 1899.

Application filed December 27, 1898. Serial No. 700,460. Term of patent 7 years.

To all whom it may concern:

Be it known that I, LEWIS C. MYERS, a citizen of the United States, and a resident of the borough of Brooklyn, in the city of New York, in the county of Kings and State of New York, have invented and produced a new and original Design for a Frame for Spring-Scales, of which the following is a specification, reference being had to the accompanying drawings, forming part thereof.

Figure 1 is a rear elevation of a frame for spring-scales embodying my design. Fig. 2 is a side elevation of the same. Fig. 3 is a plan view thereof, and Fig. 4 is a front elevation of the same.

As shown, the base 1 is circular in outline and terminates centrally in a short upwardly-extending neck 2, above which is supported an oblong and substantially rectangular back piece 3, in front of which is a circular vertically-arranged plate 4. The back piece 3 is of a length nearly equal to the vertical diameter of the front plate, but is of a thickness very much less than the diameter of the front

plate measured crosswise and is arranged to project centrally and rearwardly therefrom, as well as upwardly and substantially centrally from the circular base-plate, which is arranged at right angles to the circular front plate.

The leading feature of the design consists in the comparatively narrow back piece connecting centrally with the circular front plate and also projecting upwardly and substantially centrally from the base-plate.

What I claim as new, and desire to secure by Letters Patent, is—

The design for a frame for spring-scales as herein shown and described.

Signed at the borough of Manhattan, in the city of New York, in the county of New York and State of New York, this 21st day of December, A. D. 1898.

LEWIS C. MYERS.
